SOIL PULVERIZER

Joseph F. Rhodes, South Pasadena, Calif.

Application March 7, 1934, Serial No. 714,485

10 Claims. (Cl. 97—215)

This invention relates to soil working machines.

The general object of the invention is to provide an improved rotary member for pulverizing soil.

Another object of the invention is to provide a novel soil pulverizer blade and mounting therefor.

Other objects and the advantages of this invention will be apparent from the following description taken in connection with the accompanying drawing, wherein:

Fig. 1 is an elevation partly in section showing details of the rotor.

Fig. 2 is a fragmentary elevation showing details and

Fig. 3 is a diagram showing the arrangement of cutting knives.

Referring to the drawing by reference characters I have shown my invention as embodied in a soil pulverizer which includes a bearing block

25 which supports one end of a shaft 41. This shaft 41 is provided with a plurality of annular sheet steel spider members 42. Each of these members is preferably made in two parts as shown in Fig. 1 and the two parts are secured together by straps or plates 43 and bolts or other fastening means 44.

The sheet steel members 42 are clamped between flanges 45 and are held by bolts 46, as shown in Fig. 1. These flanges 45 are arranged on semi-cylindrical sleeves 47 which are provided with flanges 48 secured together by bolts 49 and the structure is such that the spider members 42 are rigidly held upon the shaft 41.

The sheet steel spiders 42 are shaped to provide

a rim portion 53 in the periphery of which are arranged spaced slots 54. Two of the walls of these slots are preferably at right angles to each other while the third wall shown at 55, Fig. 2, is inclined towards the opposed wall. Blade sup-

ports are shown at 56 and include base portions 57 shaped to fit the slots 54 and an end portion 58 which overlays the adjacent part of the spider rim 53.

Clamping members 58' have an end portion 59 which engages the periphery of the rim portion 53 and are secured in place by bolts 60 which pass through the clamping members, the portion 53 and the end portions 58 to hold the blade supports in position.

Mounted upon the blade supports I show straight blades 61 which are held in place by bolts 61'. These blades are provided with opposed bevelled edges 62 so that they are reversible.

The arrangement of the blades is preferably as shown in Fig. 3 and as here shown includes an outer set A, an intermediate set B, a second inter-

mediate set C and another outer set D, although it will be understood that the number of sets of blades may be varied and the blades may be symmetrical or offset to one side of the tractor depending upon the condition under which the machine is working.

The arrangement of blades is such that the forward edge 62' of a blade in set A first engages the soil then the entire blade gradually enters the soil and just as the end 63 of the blade in set A is leaving the soil the end 64 of the blade in set B enters the soil. Just before the end 65 of the blade in set B leaves the soil the end 66 of the blade in set C enters the soil and so on so that the cutting action is gradual and there is no undue shock given the rotor.

In operation, the rotor is arranged at the desired cutting depth and as it advances and the soil is engaged by the rapidly rotating blades 61 it is thoroughly cut up, and the soil, cover crop, insects, etc., are thrown into and through the rotor in a thoroughly pulverized condition.

From the foregoing description it will be apparent that I have invented a novel type of soil pulverizer which is highly efficient in use, which can be economically manufactured, and which is not likely to get out of order.

Having thus described my invention, I claim:

1. In a soil pulverizer, a rotor comprising a pair of spaced disks, each of said disks having a series of peripheral notches therein, blade supports having projecting portions thereon fitting said notches, and means to hold said blade supports in position.

2. In a soil pulverizer, a rotor, said rotor comprising a pair of sheet metal spiders, each of said spiders having a rim with a series of peripheral notches therein, blade supports having projecting portions thereon fitting said notches, clamping members engaging said blade supports and holding means passing through said clamping members, said blade supports and said spiders.

3. For use in a soil pulverizer, a rotor comprising a plurality of spaced spiders, each of said spiders having a series of peripheral notches therein, blade supports having projecting portions thereon fitting said notches, clamping members engaging said blade supports and fastening means passing through said clamping members, said blade supports and said spiders.

4. In a soil pulverizer, a rotor shaft, a plurality of pairs of semi-circular spiders arranged about said shaft, means to clamp each pair of semi-circular spiders together and to the rotor shaft, blade supports mounted on said spiders,

cutting blades mounted on said blade supports, said cutting blades being arranged in a plurality of sets, the blades of each set being parallel to each other and having their cutting edges inclined relative to the axis of the rotor.

5. In a rotor for a soil pulverizer, a shaft, a rotor on said shaft, a shield associated with said rotor, and movable therewith, means to simultaneously lift said shield and said rotor, a skirt 10 hinged to said shield, a second skirt hinged to said first skirt and cultivator teeth in said second skirt.

6. In a rotor for a soil pulverizer, a shaft, a plurality of spiders mounted on said shaft, a plurality of sleeves on said shaft, one of said sleeves being arranged adjacent each side of each spider, each of said sleeves comprising a pair of members having semi-cylindrical cavities therein, said shaft being received in the semi-cylindrical 15 cavities, means to hold said sleeve members assembled, each of said spiders having a series of peripheral notches therein, a blade support including a projecting portion fitting said notches and a blade on said support.

20 7. In a rotor for a soil pulverizer, a shaft, a plurality of pairs of sleeves mounted on said shaft, a spider member arranged between each pair of sleeves, each of said spiders having a series of peripheral notches therein, blade supports 25 having base projecting portions thereon fitting said notches and means to hold said blade supports in position and blades on said blade supports, each of said blades having each edge bevelled to render the blades reversible.

30 8. In a rotor for a soil pulverizer, a shaft, a plurality of pairs of semi-cylindrical sleeves mounted on said shaft, each of said semi-cylindrical sleeves having a pair of flanges thereon, means uniting the flanges of each pair of semi-cylindrical sleeves, a sheet steel spider member, 35 said spider member comprising a pair of semi-circular members clamped between flanges on said sleeves, said spider members having plates thereon at the outer edge thereof securing said

members together, each of said spiders having a series of peripheral notches therein, blade supports having projecting portions thereon fitting said notches and means to hold said blade supports in position.

9. In a rotor for a soil pulverizer, a shaft, a plurality of spiders mounted on said shaft, each of said spiders comprising a pair of semi-circular members, abutting along the diameter thereof and including a rim portion, means adjacent the 10 rim portion to unite each pair of spider portions, a plurality of sleeves on said shaft, one of said sleeves being arranged adjacent each side of each spider, each of said sleeves comprising a pair of members having semi-cylindrical cavities therein, said shaft being received in the semi-cylindrical cavities, means to hold said sleeve members assembled, each of said spiders having a series of peripheral notches therein, a blade support including a body engaging the rim and also 15 including a projecting portion fitting said notches and a blade on said support.

10. In a rotor for a soil pulverizer, a shaft, a plurality of spiders mounted on said shaft, each of said spiders comprising a pair of semi-circular 20 members abutting along the diameter thereof and including a rim portion, means adjacent the rim portion to unite each pair of spider portions, a plurality of sleeves on said shaft, one of said sleeves being arranged adjacent each side of each spider, each of said sleeves comprising a pair of members having semi-cylindrical cavities therein, said shaft being received in the semi-cylindrical cavities, means to hold said sleeve 25 members assembled, each of said spiders having a series of peripheral notches therein, said notches being of increasing width towards the axis of said spiders, a blade support including a body engaging the rim and also including a projecting portion fitting said notches and a clamping member 30 engaging said blade supports and holding means passing through said clamping members, said blade supports and said rim portions.

JOSEPH F. RHODES.
